PACKAGING EXPLOSIVES

Theron F. Pauls, Alton, Ill., assignor to Olin Industries, Inc., East Alton, Ill., a corporation of Delaware

Application June 17, 1950, Serial No. 168,735

2 Claims. (Cl. 206—65)

1

This invention relates generally to the packaging of explosives, and particularly to a prepared package containing cups charged with explosive.

Blasting caps, detonators, and the like consist essentially of a cup, usually metallic, charged with highly sensitive explosive. These are frequently handled in commerce with one end of the cup open so that, at the time of its use, the miner or other user may insert an appropriate fuse or electric igniter and crimp the cup to the fuse or igniter. Since the explosive contained within the open-ended cup is dry, though usually compacted into a more or less coherent mass, there is an inherent danger that some of the explosive may escape through the open end of the cup, even though the cups be arranged with their open ends up. The hazard involved in the shipment of such explosive-laden cups has led to the requirement laid down by the Interstate Commerce Commission that such open-ended cups must be covered by a suitable elastic pad, which serves the purpose not only of confining the explosive to its cup, but provides cushioning for the cups.

In compliance with the regulation aforesaid, it has been customary heretofore to pack explosive-laden cups so that their open ends are up, and the packages heretofore in use have been designed so that, when the package is opened, access is had to the pad, which must be removed before access to the cups can be had. With such arrangements, when the package is opened, and one of the cups made accessible, all have their open ends exposed upwardly, thus inviting reception of foreign objects and materials. This presents not only a hazard from the standpoint of possible explosions, but the foreign materials which find their way into the open end of the cups may be of character such as to adversely affect the utility of the explosive charge contained within the cups.

The object of the present invention, generally stated, is to provide a prepared package containing open-ended cups charged with explosive and in which the package is not only safe to handle, but after being open, affords protection for the cups remaining therein.

Other objects will become apparent to those skilled in the art when the following description is read in connection with the accompanying drawings, in which:

Figure 1 is a perspective view of a package of detonators prepared in accordance with one embodiment of the present invention;

2

Figure 2 is a perspective view of the components of the package shown in Figure 1 without the exterior wrapper;

Figure 3 is a perspective view of a component 5 of the package shown in Figure 1, illustrating the condition thereof at the time it is initially laden with detonators and before assembly with the other components;

Figure 4 is a perspective view of a package 10 prepared in accordance with another embodiment of the invention and ready to be loaded with detonators; and

Figure 5 is a perspective view of the package 15 shown in Figure 4 when laden and ready to be wrapped.

The present invention contemplates the packing of explosive-charged cups, typified by detonators, in a tray with the open ends of the detonators at the open face of the tray. In accordance with the required practice, the open ends of the detonators are covered by a pad of elastic material, such as paperboard or felt, and the assembly of tray, detonators, and pad is wrapped so that the most accessible opening 25 to the wrapping is at a face of the tray which is at right angles to the open ends of the detonators. The face of the tray last-mentioned is preferably provided with a section readily rupturable, so that access may be had to the packed 30 detonators through that face of the tray, and a detonator may be removed from the package in a direction parallel to the pad, and while the pad remains in position across the open mouths of other detonators in the package.

The invention further contemplates the assembly together of two trays laden with detonators, as above described, so that the open ends of the detonators in the respective trays face each other, and the elastic pad is interposed therebetween, thus serving to cushion and close the mouths of detonators on opposite sides thereof. The assembly of two such trays of detonators with the intervening pad is enclosed in a suitable outer package or wrapping of any desired form and of any suitable material, but preferably the wrapper has a closure which, when opened, exposes those walls of the respective trays which, as pointed out above, are readily openable.

Referring now to Figure 3, a series of detonators 1, which are in the form of metallic cups having an open end 2 and charged with explosive, are packed snugly in a tray 3. The tray 3 is a five-walled structure, i. e., having a bottom 4, a pair of end walls 5, and a pair of side walls 6. 55 The tray may be formed of a suitable blank of

soft paperboard carefully proportioned so that a given number of detonators fits snugly therewithin. In the embodiment shown, one of the side walls 6 of each tray is provided with lines of spaced perforations 7, delineating a readily separable section, which may be torn out to fully expose the axial faces of the detonators 1 contained within the tray.

Two such trays 3, when filled with detonators in the manner aforesaid, are turned so that their side walls, opposite the one having the series of perforations 7, constitute the bottom, and the open ends 2 of the detonators are at the side, as shown in Figure 2. With the arrangement shown, the open ends of the detonators 1 face each other and abut a pad 8 on opposite sides thereof. The pad 8 serves to close the mouths of these detonators in both trays and to cushion the ends of the same.

The assembly of trays, detonators, and pad, arranged as shown in Figure 2, is then encased in a suitable exterior box or wrapping, as shown in Figure 1. The exterior wrapping may take any convenient form, such as a paperboard box 9 having a hinged lid 10. Irrespective of the character of the box 9, it is preferable that said box be provided with a closure portion, such as 10, which constitutes the avenue through which the consumer is invited to gain access to the contents, and may normally be expected to do so. The invention contemplates that the access opening to the wrapping 9 be preferably arranged so that, when the closure for said opening is lifted, the sides of trays 3, which have the lines of perforations 7, will be thereby exposed. With such an arrangement, access may be had to the detonators in the package by grasping the edge 11 of the exposed side wall 6 and tearing it along perforation lines 7 in the manner shown in Figure 1. With the section thus removed from the side wall of the tray, the individual detonators 1 may be readily removed from their packed position by lifting them upwardly, i. e., in the direction parallel with pad 8, and without disturbing the relation of the pad 8 with reference to the detonators remaining in that or the opposite tray. Such detonators as remain in the tray continue to have their mouths closed and continue to be protected by the pad 8.

A modified form of the package is shown in Figures 4 and 5 wherein two trays 13 are formed from a single blank of material so as to provide a double wall 14 folded along a line 15, one ply of which constitutes the side wall of one tray, and the other ply constitutes the side wall of the other tray. The side walls 16 opposite that just mentioned in each tray are provided with lines of spaced perforations 7' in order that a section of said side wall may be readily separated from the body of the tray.

The respective trays 13 are packed with detonators in precisely the same manner as that described above in connection with the tray 3, so that the open ends of the detonators extend up (in the position shown in Figure 4). When the respective trays are filled with detonators, the trays are turned on their sides, as shown in Figure 5, so that the wall 14 makes opposite right angle bends at line 18 and is interposed between the respective tray-loads of detonators which, as in the previous embodiment, have their open ends facing each other. In this embodiment, the ex-

tension 17, which is preferably integral with the two trays 13 (but may be a separate piece adhered to them), performs the function of the pad 8 in the previous embodiment.

Finger slots 19 may be provided at the perforated wall of the trays in either embodiment.

The interior package shown in Figure 5 is preferably provided with a suitable wrapping, or outer case, such for example, as that shown in Figure 1, wherein, when the closure flap is opened, the sides of the trays which have lines of perforations are exposed.

From the foregoing description, those skilled in the art should readily understand that the invention accomplishes its objects and provides a package of explosive-charged cups, which is not only safe to handle while the package is intact, but affords continued protection to the detonators remaining in the package after it has been opened and some have been removed.

While two complete embodiments of the invention have been disclosed, it is apparent that many modifications and variations in the details thereof will present themselves to those skilled in the art without departing from the spirit of the invention, and it is therefore to be understood that such modifications and variations are contemplated by and within the scope of the appended claims.

Having thus described the invention, what is claimed and desired to be secured by Letters Patent is:

1. A prepared package comprising a pair of trays each having five walls secured together and an open side, a multiplicity of cups charged with explosive, said cups being divided equally between and arranged in said trays with their open ends at the open side of said trays, said trays being arranged with their open sides facing each other, a pad between said trays and engaging the open ends of the cups in both trays, and a wrapper having parts surrounding said trays and said pad and maintaining the same in the relation aforesaid, said wrapper having a closure flap at one face, said closure flap being openable without releasing the relationship of said parts, and the wall of each of said trays, at the face which is exposed when said closure flap is open, being scored to delineate a readily separable section of tray-wall, said section extending to the closed ends of the cups, and said section when separated providing an opening through which the cups are accessible without removing the trays from the wrapper and without removing the pad from engagement with the other parts.

2. The package of claim 1 wherein the face at which the separable section is located is parallel with axes of the cups within the package.

HERON F. PAULS.
